UNITED STATES PATENT OFFICE.

WILLIAM A. CAHILL, OF SYRACUSE, NEW YORK.

CARBURETER.

No. 878,770.

Specification of Letters Patent.

Patented Feb. 11, 1908.

Application filed March 14, 1907. Serial No. 362,265.

To all whom it may concern:

Be it known that I, WILLIAM A. CAHILL, a citizen of the United States, and resident of Syracuse, in the county of Onondaga, in the State of New York, have invented new and useful Improvements in Carbureters, of which the following, taken in connection with the accompanying drawings, is a full, clear, and exact description.

10 This invention relates to carbureters of that class comprising a casing for containing gasoline or other fluid and embodying a chamber in which the gasoline is combined with air so as to produce a vapor designed to be supplied to the cylinder of an explosive engine.

The chief object of the present invention is to produce a carbureter of that character in which the air and gasoline shall be drawn 20 into the mixing-chamber by suction created therein by the action of the piston in the engine-cylinder, and to provide said mixing-chamber with a gasoline-sprayer rendered operative by the suction of the gasoline into 25 the chamber, and to associate with said sprayer a screening-device or other suitable means serving to reduce the particles of gasoline-spray to a maximum degree whereby the two elements will be thoroughly combined 30 and supplied to the engine-cylinder in an absolutely vaporized condition and thus increase the efficiency of an explosive-engine.

A further object of my invention is to produce a carbureter which shall be very simple 35 in construction, reliable and effectual in its operation, and at the same time will greatly economize in the use of gasoline and permit, of convenient and positive regulation of the feed of the air and gasoline.

40 To that end the invention consists in the novel arrangement and combination of the component parts of the carbureter as hereinafter fully described and set forth in the claims.

45 In the accompanying drawings, Figure 1 is a vertical section of the carbureter embodying my invention; Fig. 2 is a vertical section on line —U—U—; and Figs. 3, 4, 5, 6 and 7 are transverse sections taken on the lines —V—V—, and —W—W—, —X—X—, —Y—Y—, and —Z—Z— respectively.

Referring to the drawings —1— denotes an upright cylindrical casing which is pro-

vided with a top —2— which is secured removably thereon by means of screws —3— 55 —4—5— formed on the respective parts.

—6— represents a conical-shaped cup disposed within the casing and held in position by a flange —7— formed on said cup and clamped between the aforesaid flanges —4—5—. This cup serves as a gasoline drip, as will be hereinafter fully explained, and divides the casing transversely so as to form a lower chamber —A— for containing a suitable quantity of gasoline, and an upper chamber —B— in which the mixture of gasoline and air is effected.

To the bottom of the casing is connected a pipe —8— which extends from a suitable tank or reservoir (indicated at 9) for storing the gasoline. This pipe communicates with a stand-pipe —10— extending into the chamber —A— and is provided with the well known so-called needle-valve —11— which may be adjusted to regulate the supply 70 of gasoline to the chamber —A—. The pipe is also provided with the usual valve —12— by which the supply from the tank or reservoir may be cut off if desired.

The stand-pipe —10— is disposed at one side of the center of the chamber and is of such length as to maintain the level of the gasoline in the chamber a proper distance below the bottom of the conical cup —6—. In the center of the chamber —A— are disposed two concentrically arranged pipes —13—14— which are open at both ends and extend from the bottom of the casing through the lower end of the cup —6— so as to carry the pipes into the upper chamber 85 —B—. These pipes are arranged with a space between them and thus two air-inlets —15—16— are provided, and the opening —17— in the lower end of the cup for the reception of the pipes is sufficiently large to afford communication between the cup and lower chamber —A— for the purpose shortly 90 explained. These inlets I term main and auxiliary passages respectively.

—18— denotes a small upright tube extending from the bottom of the chamber —A— and having its upper end portion passing through the opening —17— in the lower end of the cup —6— and terminating in a right angled bend —18— provided with 100 a longitudinal slit —19— as clearly shown 105

in Figs. 1 and 2. The lower end of the tube —18— is connected to a well known "needle-valve" —20— suitably fastened in the chamber —A— and communicates with the 5 said chamber by means of a small port —21— in the valve as shown in Fig. 1. This valve has its stem projecting at the exterior of the casing and serves to regulate the feed of gasolene to the chamber —B— in which 10 the mixture of the two elements is effected. The upper bent and slotted end of the tube —18— constitutes a sprayer for the gasolene and terminates directly over the central or main air-inlet passage —15—.

15 It will be understood that the gasolene is drawn into the chamber —A— from the storing-tank or reservoir by the suction created in the casing by the piston of the engine-cylinder (not necessary to be shown). 20 This suction obviously draws the gasolene through the tube —18— from the chamber —A— into the upper chamber —B—, and also draws air through the passage —15—16—. The draft of the gasolene through said tube 25 and resultant spraying action in conjunction with the direct draft of the air through the main or central passage —15— results in combining a greater portion of the air with the particles or molecules of gasolene produced, and the action of the air rushing up 30 through the auxiliary or surrounding passage —16— reduces these particles or globules to some degree, thus completing the primary step in effecting the mixture of the 35 two elements. As a final step in the mixture of the two elements, I provide the chamber —B— with a set of transverse finely perforated diaphragms or screens, preferably two screens —22—23—, disposed 40 above the sprayer and arranged one over the other and a suitable distance apart. Each of these screens is preferably composed of wire-cloth of extremely fine mesh and has its margin secured between two rings —24— 45 —24— united by screws —25—25— as illustrated in Fig. 5 and the two screens are detachably fastened upon the cup —6— by means of screws —26—26— passing through 50 apertures in the rings and entering the top of said cup as clearly shown in Fig. 1. The lower screen is preferably formed flat and is provided in the center of its top with a small cone —27— also composed of wire-cloth. The upper screen I prefer to form conical 55 and provide the top with a correspondingly shaped imperforate metal cap —28— suitably secured to the center thereof.

60 The suction of the mixture of air and gasolene through the screens or diaphragms constructed and arranged in the manner described, produces a thorough vaporization of the mixture, which is supplied to the usual compression-chamber in the explosion-cylinder of the engine through the 65 usual pipe —29— connected to a neck —30—

projecting from the center of the top —2—. The outlet-opening —31— of said neck is provided with a suitable check-valve —32— which is opened by the suction of the vapor through the pipe —29—. This valve will 70 close automatically at the end of the suction-stroke of the piston, it being understood that the communication between the pipe and engine-cylinder is cut off by the usual automatically closing intake-valve. To relieve the pipe —29— of any back pressure that may exist, I provide a suitable valve —33—. In order to observe the quantity 75 of gasolene in the chamber —A— to determine whether the needle-valves —11— and —20— are properly adjusted, I provide the casing with a glass-gage —34—.

80 While the aforesaid wire-cloth cone —27— and conical metal cap —28— are not absolutely essential to the action of the carbureter, still at the same time it has been found by experience that they assist quite materially in the vaporization of the mixture. In case the screens become excessively moist by continued use, the drips therefrom will enter the 85 cup —6— and pass through the opening —17— into the chamber —A—.

90 What I claim as my invention is:—

1. In a carbureter, the combination of a 95 casing provided with a liquid-containing chamber having a suitable source of supply, and a mixing-chamber having a suitable outlet-opening, a central vertical air-inlet pipe extending from the bottom of the casing into the mixing-chamber, a sprayer affording 100 communication between the liquid-chamber and mixing-chamber and arranged above the air-inlet pipe, a perforated diaphragm disposed in the mixing-chamber, and a suction-pipe connected to the mixing-chamber 105 at the outlet-opening for the purpose set forth.

2. In a carbureter, the combination of a 110 casing provided with a liquid-containing chamber having a suitable source of supply, and a mixing-chamber disposed above the liquid-containing chamber and having a suitable outlet-opening, a central vertical air-inlet passage extending from the bottom of the casing through the liquid-containing 115 chamber and into the mixing-chamber, a passage for feeding the liquid from the lower chamber into the mixing-chamber, a sprayer at the upper end of the latter passage and disposed at an angle to the air-inlet passage, a drip-cup supported in the bottom of the mixing-chamber and communicating with the liquid-containing chamber, and a screen 120 mounted on the drip-cup and disposed above the air-inlet passage and sprayer as set forth.

3. In a carbureter, the combination of a 125 casing provided with a liquid-containing chamber and a mixing-chamber, a drip-cup in the bottom of the mixing-chamber, an 130

air-inlet pipe extending through the bottom of the drip-cup into the mixing-chamber, means for feeding the liquid into the mixing-chamber including a sprayer disposed transversely above the air-inlet pipe, a series of screens arranged one over another within the mixing-chamber and supported upon the drip-cup, and a suction-pipe connected to the said mixing-chamber above the screen for the purpose set forth.

4. In a carbureter, the combination of a mixing-chamber provided with an air-inlet pipe and a gasoline feed-pipe disposed at one side of the air-inlet pipe and parallel thereto, means for spraying the gasoline across the inner end of said air-inlet pipe, and a suction-pipe connected to said chamber as and for the purpose set forth.

5. In a carbureter, the combination of a casing, a drip cup dividing the casing into a lower liquid-containing-chamber and an upper mixing-chamber, a passage for supplying the mixing-chamber with air, means for spraying the liquid above the air-passage, a screening-device disposed above the air-supplying means and liquid-spraying means, and supported on the drip-cup and suction means communicating with the mixing-chamber above the screening-device as and for the purpose set forth.

6. In a carbureter, the combination of a casing, a drip-cup dividing the casing into a lower gasoline-containing chamber and an upper mixing-chamber, a central vertical air-inlet pipe extending from the bottom of the casing through the bottom of the drip-cup, a gasoline-feed communicating with said mixing-chamber and provided with a sprayer disposed above the air-inlet pipe, a conical screen disposed in the mixing-chamber above the air-inlet pipe and gasoline-sprayer and supported on the drip-cup, and a suction-pipe connected to the said mixing-chamber above the screen as and for the purpose set forth.

7. In a carbureter, the combination of an upright casing having a gasoline-containing chamber provided with a suitable source of supply, and a mixing-chamber disposed above the gasoline-chamber, an air-inlet-pipe extending from the bottom of the casing into the mixing-chamber, a tube for feeding the gasoline from the containing-chamber to the mixing-chamber and provided with a sprayer arranged directly over the air-inlet-pipe, a valve for regulating the supply of gasoline to the containing-chamber, a valve for regulating the feed of gasoline from the latter chamber to the mixing-chamber, a flat-screen disposed in the mixing-chamber above the air-inlet pipe and sprayer, a conical-screen arranged above the flat-screen, and a suction-pipe connected to the top of the mixing-chamber as and for the purpose set forth.

8. In a carbureter, the combination of a casing, a drip-cup dividing the casing into a lower gasoline-containing chamber and an upper mixing-chamber, a gasoline supply-pipe connected to the lower chamber, a main air-passage and an auxiliary air-passage extending from the bottom of the casing through the drip-cup and into the mixing-chamber, means for feeding the gasoline from the lower chamber to the mixing-chamber and including a transversely arranged sprayer disposed above the main air-passage, and suction means operative for drawing the air and gasoline into said mixing-chamber as set forth.

9. In a carbureter, the combination of a casing, a drip-cup dividing the casing into a lower gasoline-containing chamber and an upper mixing-chamber, means supplying the gasoline to said lower chamber, two concentrically arranged pipes extending centrally and vertically from the bottom of the casing through the bottom of the drip-cup and into the mixing-chamber, the inner pipe forming a main air-inlet and the space between the two pipes constituting an auxiliary air-inlet, a gasoline feed-tube extending through the bottom of the drip-cup into the mixing-chamber and provided at its discharge end with spraying means disposed over the main air-inlet, and a suction-pipe connected to the upper portion of the mixing-chamber as and for the purpose set forth.

10. In a carbureter, the combination of a casing, a drip-cup dividing the casing into a lower gasoline-containing chamber and an upper mixing-chamber, a stand-pipe disposed in the gasoline-chamber and open through the bottom of the casing, a supply-pipe connected to the lower end of said stand-pipe, a vertical air-pipe passing through the bottom of the casing and drip-cup and extending into the mixing-chamber, a tube for feeding the gasoline from the lower chamber to the mixing-chamber and provided at its discharge end with a sprayer disposed transversely in relation to the air-pipe, and a suction-pipe connected to the top of the mixing-chamber as and for the purpose set forth.

11. In a carbureter, the combination of a casing having a lower gasoline containing-chamber and an upper mixing-chamber, a supply-pipe connected to the gasoline-chamber, a valve for regulating the supply, an air passage extending from the exterior of the casing into the mixing-chamber, means for feeding the gasoline from the lower chamber to the mixing chamber and including a sprayer, a valve for regulating the feed of gasoline, a screen disposed in the mixing-chamber above the sprayer and air-passage, the upper portion of the mixing-chamber being provided with an outlet opening, a suction-pipe communicating with the outlet.

opening, and an automatically closing valve in said opening as set forth and shown.

12. A carbureter comprising a gasolene-chamber provided with a stand-pipe, a suitable source of supply connected to said stand-pipe, a mixing-chamber having a vertical air-inlet pipe extending through the gasolene-chamber, a vertical pipe for feeding the gasolene into the mixing-chamber, a sprayer 10 at the upper end of said feed-pipe and disposed at right angles to the air-inlet pipe, a drip-cup at the bottom of the mixing-chamber and communicating with the gasolene-chamber, and a suction-pipe connected to the said mixing-chamber and provided with an automatic check-valve as and for the purpose set forth.

13. A carbureter comprising a gasolene-chamber, a mixing-chamber having an air-inlet, means for feeding the gasolene to the mixing-chamber, a drip-cup formed with a flange by which it is secured within the mixing-chamber and provided with an opening by which it communicates with the gasolene-chamber, a screen disposed in the mixing-chamber above the air-inlet and gasolene-feeding means and supported on the drip-cup, and a suction-pipe connected directly to the mixing-chamber above the screen as and for the purpose set forth.

14. A carbureter comprising a gasolene-chamber, a mixing-chamber having a drip-cup communicating with the gasolene-chamber, a pipe for supplying air to the mixing-chamber, means for feeding the gasolene to the mixing-chamber, a screen supported on top of the drip-cup and arranged above the air-inlet and gasolene-feeding means, and a suction-pipe connected to the top of the mixing-chamber as and for the purpose set forth.

15. A carbureter comprising a gasolene-chamber, a mixing-chamber having a drip-cup at its bottom communicating with the gasolene-chamber, a pipe extending through the bottom of the drip-cup for supplying air to the mixing-chamber, means for feeding the gasolene to the mixing-chamber and including a sprayer disposed at the air-inlet pipe, a conical screen supported on top of the drip-cup, and a suction-pipe communicating with the mixing-chamber above the screen as set forth.

16. In a carbureter, the combination of an upright casing provided with a removable cup dividing the case into a lower gasolene-containing-chamber and an upper mixing-chamber, a pipe extending centrally and upwardly from the bottom of the casing through the bottom of the cup for supplying air to the mixing-chamber, a tube extending from the gasolene-chamber up through the cup for feeding gasolene to the mixing-chamber, and provided at its upper end with a sprayer disposed over the adjacent end of the air-pipe, a flat-screen and a conical screen

disposed one above the other and supported on top of the cup, and a suction-pipe connected to the mixing-chamber above the screens as and for the purpose set forth.

17. In a carbureter, the combination with 70 an upright cylindrical casing, of a cone-shaped drip-cup dividing the case into a lower gasolene-containing-chamber and an upper mixing-chamber and provided with an opening affording a communication between 75 the mixing-chamber and gasolene-chamber, two vertical concentrically arranged pipes extending from the bottom of the casing through the opening in the cup and forming an inner main air-passage and an outer auxiliary air-passage, a gasolene feed-tube extending from the lower portion of the gasolene-chamber through the said opening and provided with spraying-means over the main air-passage, a plurality of screens mounted 80 on top of the drip-cup and arranged one above the other, the top of the mixing-chamber being provided with an outlet-opening, a check-valve in said opening, and a suction-pipe communication with said opening as 85 and for the purpose set forth.

18. In a carbureter, the combination of an upright cylindrical case formed with an exterior circumferential flange, and having a removable top formed with a corresponding 95 flange, a cup disposed within the casing and formed at its upper portion with a flange secured movably between the flanges of the casing and top, said cup dividing the casing into a lower gasolene-chamber and an upper 100 mixing-chamber, and air-passage extending from the exterior of the chamber to the mixing-chamber, means for feeding the gasolene to the said mixing-chamber, a screen secured detachably to the top of the cup, the top of 105 the casing being formed with an outlet-opening, a check-valve in the opening, and a suction-pipe communicating with said opening as and for the purpose set forth.

19. In a carbureter, the combination with 110 the mixing-chamber having suitable air- and gasolene-inlets, and a suction-pipe connected to the mixing-chamber, of a conical screen secured removably in the said mixing-chamber and provided with a sheet-metal cap as 115 set forth and shown.

20. In a carbureter, the combination of a casing divided into a gasolene-containing chamber and a mixing-chamber, a suitable air-inlet passage extending through the gasolene-chamber and into the mixing-chamber, and a feed-tube extending from the bottom of the gasolene-chamber into the mixing-chamber, the discharge-end of said tube being provided with a slit disposed above the 125 air-inlet passage and serving as a sprayer as set forth and shown.

21. In a carbureter, the combination of a gasolene-containing chamber having a suitable source of supply, a mixing-chamber 130

arranged above the gasoline-chamber, a vertically disposed air-inlet pipe extending into the bottom of the mixing-chamber, and a vertically disposed tube for feeding the gasoline to the mixing-chamber, said feed-tube having its upper end portion bent horizontally over the air-inlet and provided with

a central longitudinal slit serving as a sprayer as and for the purpose described.
